US00D759545S

(12) **United States Design Patent**
Sato et al.

(10) **Patent No.:** US D759,545 S
(45) **Date of Patent:** ** Jun. 21, 2016

(54) **MOTOR VEHICLE AND/OR TOY REPLICA THEREOF**

(71) Applicants: **Jinichi Sato**, Saitama (JP); **Ken Iwasaki**, Hachiouji (JP); **Chung Lee**, Ann Arbor, MI (US)

(72) Inventors: **Jinichi Sato**, Saitama (JP); **Ken Iwasaki**, Hachiouji (JP); **Chung Lee**, Ann Arbor, MI (US)

(73) Assignee: **Toyota Jidosha Kabushiki Kaisha**, Toyota-shi, Aichi-ken (JP)

(**) Term: **15 Years**

(21) Appl. No.: **29/541,929**

(22) Filed: **Oct. 9, 2015**

(57) **CLAIM**

The ornamental design for a motor vehicle and/or toy replica thereof, as shown and described.

DESCRIPTION

FIG. 1 is a front perspective view of a motor vehicle and/or toy replica thereof showing our new design;

FIG. 2 is a rear perspective view thereof;

FIG. 3 is a front view thereof;

FIG. 4 is a rear view thereof;

FIG. 5 is a right side view thereof;

FIG. 6 is a left side view thereof; and,

FIG. 7 is a top plan view thereof.

The bottom view of the motor vehicle forms no part of the claimed design.
